UNITED STATES PATENT OFFICE.

ABRAHAM STEINBERG, OF CHICAGO, ILLINOIS, ASSIGNOR TO KINETO MACHINE COMPANY, A CORPORATION OF ILLINOIS.

STEREOPTICON ADVERTISING-CLOCK.

1,172,844.

Specification of Letters Patent.

Patented Feb. 22, 1916.

Application filed January 25, 1915. Serial No. 4,244.

To all whom it may concern:

Be it known that I, ABRAHAM STEINBERG, a citizen of the United States, and a resident of Chicago, in the county of Cook and State 5 of Illinois, have invented certain new and useful Improvements in Stereopticon Advertising-Clocks, of which the following is a specification.

This invention relates to clocks in which 10 stereopticon slides are used, with suitable lenses and lights, to project an advertisement on to a screen.

The object of this invention is to obtain a device of the kind named, by means of 15 which a plurality of advertisements may be thrown onto a screen, curtain or wall, at determined intervals; said advertisements to be surrounded by the ordinary clock numerals; with the hands of the clock approaching, but not extending to, the center 20 of the clock dial or face.

Further objects are to obtain a device of the kind named which will permit ready changing of the advertisements appearing 25 on said curtain, etc., to obtain a device which is simple in construction, of few parts, not liable to get out of order, or break, and which does not require any considerable skill to operate it.

30 In the drawings Figure 1 is a diagrammatic view, showing the relation of the frame and some of the operative parts of the device, to the stereopticon elements of the device. Fig. 2 is a rear elevation of the 35 mechanism embodying the invention. Fig. 3 a side elevation of the same. Fig. 4 a front elevation thereof. Fig. 5 is a vertical sectional view of the rotating dial and advertising plate carrier. Fig. 6, is a vertical section, on an enlarged scale, of one of the pockets of the plate carrier, showing a dial and advertising plate, inserted in said pocket, (also in section). And Fig. 7 is an 40 isometric view of a member of the frame. A reference letter applied to designate a given part indicates said part throughout the several figures of the drawings, wherever the same appears.

A is a shell or case, B a light, C a condenser; and D a lens.

50 E is a frame which is removably contained in shell A, in the chamber thereof which is lettered a. Frame E comprises standards e, e¹ and member e². Standards e 55 are provided with the horizontal portions

e³, which bring said standards from the rear to the front of the frame. Member e² is provided with the horizontal parts e⁴ and e⁵, and is attached to standard e by rivets e⁶. e⁷ is a horizontal bar of frame E.

F is the frame of the clock movement of the device, and is shown as provided with two springs, f, f, one of which is intended to actuate the striking mechanism of said movement. Frame F is secured in frame E.

G is the minute hand shaft of the clock movement, and on the end of said shaft which ordinarily projects through the dial of the clock there is placed the hour hand sleeve g, which is indicated by broken lines 70 in Fig. 2. Gear wheels H, (on the hour hand sleeve), and M, (on the minute hand shaft), are substituted for the hands which are usually placed on said sleeve and shaft.

I is a stud which is secured on one of the 75 members or standards e of frame E, and J is a gear wheel which is rotatably mounted on the end of said stud.

K is a shaft one end of which is mounted in part e of the frame E, and the other end 80 in aperture k on horizontal part e⁵ of said frame.

L is a spring on shaft l, which is mounted in frame E, and shaft K is turned, (turning the carrier mechanism of the device) by 85 means of gears consisting of N, n, n¹ and n², which form a train from shaft l to shaft K. The movement of said carrier mechanism is not continuous, and is controlled by an escapement which is presently described. 90 While the carrier mechanism is stationary the advertisement is shown on the screen, curtain, or wall within the numerals of a clock dial.

O and P, are geared rings, mounted on 95 rollers Q, to turn freely.

O¹ and P¹ are hands of a clock which are secured to rings O and P, respectively, to extend in toward the center of said rings. A portion of said hands are shown on said 100 screen, etc., to indicate the time.

S and T, respectively, are geared idlers, the teeth of which intermesh with the teeth on wheels H, M, and O, P, to transmit the rotation of said wheels M, H, to said wheels 105 O, P. Said idlers are loosely mounted on shaft K, to turn freely thereon.

The advertisements which are to be thrown on the screen, etc., are placed, (together with numerals which are arranged 110

around the advertisements, as on a clock dial), on a glass or celluloid plate, in the same manner as stereopticon slides are so placed, and the plates are mounted on the carrier R and successively brought into position to be thrown, or projected onto a screen by the stereopticon element of the device. That is, said advertisements and numerals are brought in line with the focus of the light and lens, by the rotation of said carrier. The carrier, or carrying means for successively placing said advertisements in said position, consists of hub r, which is rigidly secured to shaft K, arms r¹, which extend radially out from said hub, the tappets V and W on said arms, the disk r², and nut r³; and the escapement which determines when said carrier can be moved by spring L consists of the pivoted arm U having tables u, separated by space u¹, and the gear wheel J which is provided with the wrist pin j¹ fitting loosely in slot u².

The teeth of gear wheel J intermesh with the teeth of gear wheel M, and the revolutions which said wheel J will make in an hour is determined by the relative number of teeth in said wheels J and M. At each revolution of wheel J a tappet V and a tappet W will be permitted to pass through space or aperture u¹, and in the intervals between said passing of said tappets through said space an advertisement will be projected on the screen.

It will be observed that the tappets V are at a greater distance from shaft K than are the tappets W, hence, when a space u¹ is in position for a tappet of the V series to pass therethrough a tappet of the W series will strike on a table u; and when a tappet of the W series can pass through said space the succeeding tappet, being of the V series, will strike a table u.

X are pockets on plate R¹, and Y are advertising plates in said pockets.

Z are buttons by means of which plates Y are secured in pockets X.

The several plates Y may be changed by turning the buttons Z one quarter around from the position in which they are illustrated in Fig. 2; but I consider the better way to be to remove the nut r³ and disk r² from hub r, and to then remove the plate R¹ from the carrier R, before changing said plates.

The purpose of disk r² is to hold the plate R¹ closely to radial arms r¹, thus insuring a good focus to the several plates as the same are projected on the screen, etc.

The operation of the device is: The clock spring being wound and the clock started, the wheels H, M, and J, and the rings O and P, continuously rotate. An advertising plate and so much of hands O¹ and P¹ as are within the periphery of the advertising plate being in position to be pro-

jected on a screen, etc., the light B is turned on, the advertising plate is focused on said screen, and said portions of said moving hands are also (being nearly in focus) projected onto said screen with said plate. 70 Lever U is continuously swinging, and as the space u¹ is brought into position for a tappet (V or W) to pass therethrough, spring L will move the carrier R and plate R¹ so that the next advertising plate, (with 75 clock numerals thereon) will turn into position to be projected on the screen.

In the device illustrated eight advertising plates will be projected on the screen in an hour. I have constructed and operated a 80 device in which six advertisements are projected on a screen in an hour; and any reasonable number of said plates may be placed in a corresponding number of pockets (X) 85 on plate R¹, by merely having the arms r¹ and tappets V, W, correspond in number with said pockets.

I claim:—

1. A rotatable plate carrier comprising a hub and radial arms extending out from 90 said hub and tappets on said arms, alternate ones of said tappets being at substantially the same distance from said hubs, and adjacent tappets being at a different distance, tables spaced from each other, means to 95 rotate said carrier and means to move said tables to permit a tappet on one thereof to pass through said space, transparent plates adapted to be attached to said carrier and stereopticon means to project said plates. 100

2. A rotatable plate carrier comprising a hub and radial arms extending out from said hub and tappets on said arms, in combination with tables spaced from each other and means to move said tables, said tappets 105 positioned so that when said tables are in position for one of said tappets to pass between said tables the following tappet will strike one of said tables, and means to rotate said carrier, stereopticon plates adapted to be attached to said carrier and stereopticon means to project said plate.

3. A rotatable carrier comprising a hub and radial arms extending out from said hub, in combination with a disk adapted to fit over said hub and against said radial arms, and means to removably secure said disk in place, plates, said disk provided with means to attach said plates thereto in determined positions, and provided with apertures registering with said plates and stereopticon means to project said plates. 110 120

4. A rotatable carrier comprising a hub and radial arms extending out from said hub, in combination with a disk adapted 125 to fit over said hub and against said arms, means to removably secure said disk on said hub, pockets on said disk, and the bottoms of said pockets provided with apertures, stereopticon plates adapted to fit in said 130

pockets, means to secure said plates in said pockets, a lens and a source of light.

5. A rotatable carrier comprising a hub, radial arms on said hub and tappets on said arms, adjacent ones of said tappets positioned at different distances from said hub, in combination with a pivoted arm, spaced tables on said arm, and said arm provided with a slot, a gear wheel, a wrist pin on 10 said wheel adapted to fit and move in said slot, means to continuously move said gear wheel, stereopticon plates attachable to said carrier and means to project said plates.

6. Gears secured on the hour hand sleeve 15 and the minute hand shaft of a clock, geared rings rotatably mounted, geared idlers loosely mounted on a rotatable shaft and

adapted to intermesh with said geared wheel and geared rings, hands on said rings, said hands extending radially toward the 20 center of said rings, means to rotate said rotatable shaft, means to hold said rotatable shaft stationary, a carrier mounted on said rotatable shaft, a disk removably secured on said carrier, said plate provided with apertures, and plates removably attached to said plate to register with said apertures, and means to release said shaft at determined 25 intervals.

ABRAHAM STEINBERG.

In the presence of—

CHARLES TURNER BROWN,

CHARLES B. HEBRON.
